I. E. COLVIN

SPRAY COIL

Original Filed May 21, 1921

FIG. 1.

FIG. 3.

FIG. 2.

FIG. 4.

FIG. 5.

INVENTOR
Isaac E. Colvin

UNITED STATES PATENT OFFICE.

ISAAC E. COLVIN, OF ROCHESTER, NEW YORK, ASSIGNOR TO THE PFAUDLER COMPANY, OF ROCHESTER, NEW YORK.

SPRAY COIL.

Application filed May 21, 1921, Serial No. 471,440. Renewed June 24, 1922. Serial No. 570,718.

To all whom it may concern:

Be it known that I, ISAAC E. COLVIN, a citizen of the United States, residing at Rochester, in the county of Monroe, State 5 of New York, have invented a new and useful Improvement in Spray Coils, of which the following is a specification.

This invention relates to spray coils and the principal object thereof is to produce a 10 rigid and cheap construction whereby a liquid may be directed against the wall of a tank or some other surface in a uniform film. A preferred form of the invention is illustrated in the accompanying drawings, 15 in which—

Fig. 1 is a top plan of a spray coil embodying part of the present invention;

Fig. 2 is a side elevation of a spray coil 20 mounted on a jacketed tank;

Fig. 3 is fragmentary sectional plan view, enlarged, showing a preferred manner of attaching the coil to the tank jacket.

Fig. 4 is a sectional elevation on the line 25 4—4 of Fig. 3; and

Fig. 5 is a perspective view of a detail.

In the cooling of processed materials which are treated in jacketed tanks or containers, it has been common to flood the 30 jacket with a cold liquid, such as water or brine, so that the heat in the treated material will be rapidly absorbed. This practice is wasteful, for the reason that heat from the surrounding atmosphere is also absorbed by the liquid in the jacket and so 35 raises the temperature of the cooling medium without any corresponding benefit to the process.

If, on the other hand, the cooling liquid is 40 directed in a series of jets, against the wall of the tank only, and is not permitted to splash against the jacket, the latter becomes in effect an enclosing cover for an air space, and the external atmosphere cannot readily 45 impart heat to the cooling jets. The latter are so directed that in running down the tank walls they combine to form a thin film, which is very effective in absorbing the heat of the tank contents, requiring a minimum of cooling water or brine.

In the present instance a cylindrical tank 50 10 is indicated, having a top head 11 that is extended as at 12 to form a sealer or connecting flange between the tank wall and the surrounding jacket 13. The air space 14

enclosed by the jacket may be of suitable 55 proportions to accord with the other details.

To conveniently provide a channel whereby uniform distribution of the cooling liquid may be accomplished, a pipe or tube is formed in a single coil 15, the ends being 60 autogeneously welded. Couplings 16 are also welded to the pipe to provide inlets from the source of supply, and thus there are no 65 screwed joints which might leak. The coil as shown is slightly smaller in diameter than the jacket 13.

The preferred method of connecting the coil to the tank consists in mounting it on the sealer 12 by means of nipples 17 that 70 may be formed from short lengths of tubing, flattened and shaped as at 18 and 19, to fit the coil and the sealer, respectively. These nipples, the coil, and the sealer are connected by welding at 20 and 21, the nipples being 75 located at regular intervals as shown in Figs. 1 and 2.

To provide means whereby the cooling liquid carried through the coil 15 will be 80 directed in a series of streams or jets against the tank wall 10, without the use of separate jet heads or nozzles, diverging holes of small diameter, as at 22, are drilled through the sealer 12, within the nipples 17. To insure these holes being properly located it 85 is preferred that they be drilled after the coil has been attached to the tank. To this end openings 23 are made through the wall of the pipe, approximately conforming to the inner peripheries of the nipples 17, and other openings 24 in the outer wall of the pipe 90 have internally-threaded bushings 25, welded in place. Through the latter a drill may be inserted and operated to make the holes 22 as shown through the sealer 12 connecting the coil with the jacket space.

The threaded bushings 25 may be provided with ordinary pipe plugs 26, which when removed give access to the holes 22 so that the latter may be cleaned with a wire.

If the nipples and bushings are located at 100 suitable intervals around the coil 15, the cooling liquid when turned into the coil under a low pressure will be broken up into many small streams, all of which will merge together immediately below the point where they strike the tank wall, after issuing from the drilled holes 22. Thus the tank wall is 105 covered by a thin film of cooling liquid.

At the correct pressure the jacket will not be touched by the liquid and the latter will absorb heat only from the tank contents.

Under some manufacturing conditions a cold mass of material may be contained in the tank and it would then be desirable to direct a hot liquid, such as oil, through the coil, utilizing the same construction.

This invention is not limited to the exact details described and shown in the drawings, but may be somewhat modified, within the scope of the following claims.

I claim:-

1. The combination, with a vessel having a jacket provided with separated groups of divergent openings through its upper portion, of a pipe conforming approximately to the periphery of the jacket and having elongated openings in its inner side; nipples surrounding both said elongated and divergent openings and connecting the pipe with the jacket; and removable plugs in the pipe so located that all of said openings are accessible from the exterior when said plugs are removed.
2. The combination, with a vessel having a jacket provided with separated groups of divergent openings through its upper portion, of a pipe having elongated openings spaced in accordance with said groups of divergent openings; and nipples surrounding the elongated openings and corresponding groups of divergent openings, said nipples being welded to the pipe and to the jacket.
3. The combination, with a vessel having

a jacket provided with separated groups of openings therethrough diverging toward the vessel, of a pipe surrounding the vessel and having elongated openings co-extensive with the groups of divergent openings; nipples welded to the pipe and to the jacket so as to enclose and connect each elongated opening with a corresponding group of divergent openings; and means whereby the divergent openings may be rendered accessible from the exterior of the pipe.

4. The combination, with a vessel having a jacket provided with separated groups of divergent openings, through its upper portion, of a pipe having openings through its inner and outer peripheries; nipples connecting said pipe with said jacket, and with groups of the divergent openings, said nipples also corresponding with one set of openings in the pipe; and means whereby the divergent openings in the tank walls may be reached through said nipples.

5. The combination with a vessel having a jacket provided with a plurality of separated groups of jet openings therein directed toward the vessel, of a pipe surrounding the vessel outside the jacket having a plurality of elongated openings one for each group of jet openings, the margins of the openings in said pipe being secured to the jacket, and a plurality of removable plugs in the outer side of the pipe one opposite each of the openings therein, to permit access to the openings in the jacket.

ISAAC E. COLVIN.
